(57) **CLAIM**

The ornamental design for a washing machine, as shown and described.

DESCRIPTION

FIG. 1 is a front right perspective view of a washing machine, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the encircled portion 8 in FIG. 1;

FIG. 9 is an enlarged view of the encircled portion 9 in FIG. 1;

FIG. 10 is an enlarged view of the encircled portion 10 in FIG. 1; and,

FIG. 11 is an enlarged view of the encircled portion 11 in FIG. 7.

The even-dash broken lines illustrating portions of the washing machine form no part of the claimed design. The
